UNITED STATES PATENT OFFICE.

EUGENE N. YEHLE, OF MARYVILLE, MISSOURI.

SHADE-ROLLER ATTACHMENT.

Application filed November 24, 1924. Serial No. 751,808.

To all whom it may concern:

Be it known that I, EUGENE N. YEHLE, a citizen of the United States, and a resident of Maryville, county of Nodaway, in the 5 State of Missouri, have invented a certain new and useful Improvement in Shade-Roller Attachments, of which the following is a complete specification.

The present invention relates to shade 10 roller attachments, and aims to provide a novel and improved means of attaching shades to rollers which will permit the ready attachment or removal of the shades in case of repairs or renewals.

15 Accordingly, I have devised an improved shade attaching device of an inexpensive character in which provision is made for this ready and convenient shade attaching and removing function, and which further 20 provides for a more efficient shade securing action by virtue of the particular manner in which I attach the shade to the roller.

With these general objects in view, the 25 invention will now be described by reference to the accompanying drawing illustrating one form of construction which I have devised for embodying the proposed improvements, after which those features and combinations deemed to be novel will be particularly set forth and claimed.

In the drawing—

Figure 1 is an elevation, partly broken away, showing a shade and roller provided with an attachment constructed in accordance with the present invention;

Figure 2 is a perspective view, on a slightly larger scale, showing the sleeve member forming a part of the attachment;

40 Figure 3 is a similar view illustrating a portion of the curtain and the device engaging the same for securing it detachably to the sleeve member illustrated in Figure 2;

Figures 4 and 5 are end views of the 45 sleeve member and shade-engaging member, respectively, shown in Figures 2 and 3 respectively;

Figure 6 is a transverse section taken on the line VI—VI of Figure 1, but on an enlarged scale; and

50 Figure 7 is a detail perspective view showing a portion of the shade and its clamping member.

Referring now to the drawing in detail, this 55 illustrates the invention in connection with the usual form of curtain or shade roller 10 to which the shade 11 is usually se-

cured by means of tacks or the like. In the present case, I provide an improved form of detachable connection between the shade 11 and roller 10, and for this purpose employ a roller clamping sleeve 12 of a diameter approaching that of the roller 10, to which it is adapted to be firmly clamped, either by the spring action of the metal alone, or it may be additionally secured to 60 the roller by means of a tack or nail 14, as shown in Figures 1 and 6. As illustrated, the sleeve 12 is of split form, and one of its longitudinal edges is provided with an outturned lip or flange 15, which is designed 65 for detachable engagement with a similar lip or flange 16 formed longitudinally of the shade clamping member 17. This member is also formed with a longitudinal folded portion 18 having an inturned lip 19 70 designed for clamping engagement with that end of the shade which is to be attached to the roller 10. The member 17 is also bent 75 or curved to an extent sufficient to conform approximately to the curvature of the roller 80 and sleeve 12.

By means of this construction, it is apparent that the shade 11, when provided with the shade clamping member 17, may be readily and conveniently attached to or 85 removed from the roller by sliding the lip or flange 16 of the member 17 longitudinally within the flange or lip 15 of the sleeve 12. In this connection, it may also be pointed out that the relative arrangement of the 90 shade clamping member 17 and the lip 15 on the sleeve 12, is such that the folded portion 18 of the member 17 is in position to prevent any casual disengagement of the member 17 from the lip 15 in a transverse 95 direction, since the part 18 of course is adapted, in this position, to act as a stop shoulder limiting any such disengaging tendency.

In the practice now followed in the manufacture and sale of shades and rollers, the merchant is supplied with a stock of the shades and rollers, called stock shades, with the rollers attached, so that a roller is sold with each shade. Thus a roller is discarded 100 each time a new shade is purchased with a roller attached. The purchaser is obliged to take down his shade and have the merchant or shop man make up a new one to correspond, which often involves trimming 105 both the shade and roller to the proper size. In the improved form of construction, one

important feature of advantage is the total elimination of the cost of roller replacement, since the old roller (which wears in indefinitely) is used over again for the new shade, and the purchaser needs only order a shade of the proper size, and if any cutting is necessary of a stock shade, only the clamping strip 17 has to be shortened as the shade is trimmed to the proper width. It is also apparent that this process of repair or renewal of the shade is made extremely simple and easy for the purchaser who is only required to detach the old shade by slipping off the clamping member 17 from the lip or flange 15, and then apply the new shade just as easily and quickly as removing the old one. The sleeve 12 and its lip or flange 15 simply remains as a permanent part of the roller 10. While the tack 11 is not required, it insures against any slipping of the sleeve upon the roller, and the tack is preferably located adjacent to the lip 15 so that the head of the tack cannot possibly injure the shade, as this is caused to bridge over the tack head in passing over the lip, as clearly illustrated in Figure 6. The construction of the flange or lip 15 and member 17 is not required to be of such a size as to produce any bulging appearance in the shade on the roller; in fact, after the shade is rolled upon the roller, the difference in appearance between it and the ordinary shade and roller is so slight as to be imperceptible to a casual observer. Moreover, by the new attaching device, the shade is held so securely to the roller that it cannot be jerked off by any ordinary pulling upon the shade, and for reasons already explained the shade cannot become detached by any accidental disengagement from the roller.

Another feature of advantage lies in the fact that the device provides an improved and more accurate means of attaching the shade to the roller by a continuous connection entirely across its end edge, which insures an exact alinement of the edge the whole length of the roller.

The invention is not limited to the exact construction shown and described, as, for example, the shade attaching feature is equally applicable to metal tubular rollers in which the lip 15 could be formed as a part of the roller itself, instead of a separate sleeve. Therefore, while I have illustrated and described what I now regard as the preferred form of construction for embodying the invention, I desire to reserve all right to make such changes or modifications as may fairly fall within the scope of the appended claims.

What I claim is:

1. A device for attaching shades to rollers, comprising a sleeve adapted to be removably fitted to the roller and formed with a longitudinal outwardly projecting portion, and a shade-attaching member provided with a clamp element for detachable engagement with said longitudinal portion.

2. A device for attaching shades to rollers, comprising a split sleeve adapted to be yieldingly and removably clamped to the roller and formed with a longitudinal outwardly projecting portion, and a shade-attaching member provided with a clamp element adapted for detachable engagement with said longitudinal portion.

In witness whereof, I hereunto affix, my signature.

EUGENE N. YEHLE.
